CLAIM

U.S. PATENT DOCUMENTS

The ornamental design for a laundry bin, as shown and described.

DESCRIPTION

1,026,081 A * 5/1912 Dorais ..... 220/495.11 X
2,319,384 A * 5/1943 Callan et al. ..... 232/1 B
D142,275 S 8/1945 Kohen
2,780,402 A 2/1957 Zucker et al.
D183,283 S 7/1958 Junker et al.
D187,300 S 2/1960 Tupper
D205,966 S 10/1966 O'Neil
D256,423 S 8/1980 Backskay et al.
5,350,079 A 9/1994 Larson et al.

FIG. 1 is a front perspective view of a laundry bin;
FIG. 2 is a top plan view thereof; and,
FIG. 3 is a side perspective view thereof.

The other side view thereof is a mirror image of the side view shown in FIG. 3.

The bag shown in broken lines inserted in the laundry bin in FIGS. 1 and 3 is environmental structure shown for illustrative purposes only and does not form any part of the claimed design.
